UNITED STATES PATENT OFFICE.

JOHN P. LYNOTT, OF LOUISIANA, MISSOURI.

DESIGN FOR A STOVE.

SPECIFICATION forming part of Design No. 28,602, dated May 10, 1898.

Application filed January 24, 1898. Serial No. 667,829. Term of patent 14 years.

To all whom it may concern:

Be it known that I, JOHN P. LYNOTT, of the city of Louisiana, Pike county, State of Missouri, have invented a new and original Design for Stoves, of which the following is a full, clear, and exact description, reference being had to the accompanying drawings, forming a part thereof.

Figure 1 is a side elevation of a stove embodying my design. Fig. 2 is a plan view of the stove.

As shown in the drawings, the leading or material feature of my design consists of the base 1, which is oval in plan view, and extending upwardly through one end of said base is a cylindrical body 2, surmounted by a series of ribs 3, above which appears a crown-

shaped cap 4. Mounted upon the base 1 immediately in the rear of the body 2 is a smaller body 5, which is semicircular in plan view, and which body 5 is surmounted by a rectangular body 6, that is somewhat narrower than is said body 5. The base 1 and bodies 2 and 5 are provided with the transverse ribs or corrugations 7.

I claim—

The design for a stove, substantially as herein shown and described.

In testimony whereof I affix my signature in presence of two witnesses.

JOHN P. LYNOTT.

Witnesses:

ALBERT J. McCUALEY,
JOHN C. HIGDON.
